Primary Examiner — Mark A Goodwin(74) *Attorney, Agent, or Firm* — XSENSUS LLP(57) **CLAIM**

The ornamental design for a mobile fracturing equipment, as shown and described.

DESCRIPTION

FIG. 1 is a right side perspective view of a mobile fracturing equipment;

FIG. 2 is a left side perspective view thereof;

FIG. 3 is a right side elevational view thereof;

FIG. 4 is a left side elevational view thereof;

FIG. 5 is a top plan view thereof;

FIG. 6 is a bottom view thereof;

FIG. 7 is a rear elevational view thereof; and,

FIG. 8 is a front elevational view thereof.

The broken lines shown in the drawings illustrate portions of the mobile fracturing equipment that form no part of the claimed design.
